UNITED STATES PATENT OFFICE

2,633,142

AIR RELIEF DEVICE

William J. Woolley, Chicago, Ill., assignor to
Maid-O'-Mist, Inc., a corporation of Illinois

Application December 15, 1949, Serial No. 133,104

3 Claims. (Cl. 137—202)

1

My invention relates generally to air relief devices, and more particularly to improvements in float operated air relief devices similar to those disclosed in my prior United States Letters Patent Nos. 2,106,512 and 2,276,136, issued January 25, 1938, and March 10, 1942, respectively.

A principal object of my invention is to provide a device of improved, simplified construction for automatically venting air from any desired type of liquid containing system, in which the outer casing of the device is of one piece construction, rather than consisting of a casing, a cover therefor, and a union securing said cover to said casing, as has heretofore been the practice.

Another important object of my invention is to provide a novel connection in a device of the type described, between a valve unit and a float for controlling the operation of said valve unit, in which the valve unit can be removed from the device for replacement or service, even though the casing is of one piece construction and the valve unit is positively connected to the float at all times when the device is in operation.

Yet another important object of my invention is the provision of a valve unit for use with devices of the character described, which includes novel guide means whereby the motion of the valve relative to the valve seat is controlled to make the device more positive and dependable in operation.

A further important object of the invention is the provision of an improved connection between the casing and the liquid containing system, whereby the float within the casing follows accurately the rise and fall of liquid in said system, said connection providing for elimination of the effects of entrapped air within the casing and surface tension of the liquid, which otherwise may cause a lag between the level of liquid within the casing and that of the system.

The foregoing and such other objects, advantages and capabilities as are disclosed as this description proceeds, or which are inherent in my invention, are illustrated in the accompanying drawings, in which:

Figure 1 is a vertical central section of an air relief device embodying the features of the present invention, the valve mechanism being shown in the closed position;

Figure 2 is a fragmentary vertical central section of the device of Figure 1, showing the valve mechanism in the open position;

Figure 3 is a plan view taken in section on the line 3—3 of Figure 1;

Figure 4 is a fragmentary elevational view taken in section on the line 4—4 of Figure 1; and

2

Figure 5 is an enlarged elevational view of the valve unit, taken in section on the line 5—5 of Figure 2.

Like reference characters designate like parts in the drawing and in the description of the invention which follows.

Referring now to the drawings, and particularly Figure 1 thereof, my air relief device is shown as including a substantially tubular casing 10 to which a bonnet 11 is permanently secured, as for example by soldering 12. A substantially U-shaped bracket 13 is secured to the interior surface of the bonnet 11, and serves as a bearing support for the pin 14 about which the lever 15 turns. The other end of the lever 15 is secured by the pin 16 to an arm 17 extending from the float 18. A valve unit, designated generally by the numeral 19, extends through the bonnet 11 and the bracket 13, and is drivably connected to the lever 15. The lower end of the casing 10 is provided with a threaded pipe fitting 20 whereby the casing 10 may be coupled to a liquid containing system. A tongue-shaped member 21 is suspended in the opening 22 of the fitting 20, and is shown in Figures 1 and 4 to comprise two leg portions 23 and 24 suspended by the tab portions 25 and 26, respectively, and a tab 27 extending outwardly from between the leg portions 23 and 24 at the lower end of said member 21.

As best shown in Figure 5, the valve unit 19 comprises a threaded casing 28 having a circumferential flange 29 which seats against the bracket 13. The bore 30 of the casing 28 is threaded at 31 to receive the hollow nut 32, said nut 32 being provided with a guide portion 33 whereby the nut 32 may be turned for adjusting its position along the bore 30, for a purpose which is described fully below. A valve sleeve 34 is supported at its upper end portion by the hollow nut 32 and extends into the interior of the casing 10. The valve sleeve 34 includes a pair of flanges 35 and 36 between which is retained a packing member 37 of resilient material such as rubber, said packing member providing a hermetically sealed connection between the casing 38 and the valve sleeve 34.

A valve stem 38 is positioned within the valve sleeve 34 and is urged upwardly by the spring 39 which bears against the collar 40. The head 41 on the upper end of the valve stem 38, together with the guide portion 33 of the nut 32, acts as a stop limiting the downward movement of the valve stem 38. The lower end of the valve stem 38 is provided with a shoulder portion 42 which is insertable through the enlarged portion 43 of

the aperture 44 in the lever 15 (Figure 3), but which is drivably connected to said lever 15 when positioned in the slot 45 of said aperture 44. As is shown in Figures 1 and 3, substantially all of the aperture 44 lies in a concavity 52 in the lever 15. Referring again to Figure 5, the valve stem 38 is also provided with a cup shaped sleeve 46 which is secured to the stem 38 by the neck portion 53. The concave side of the sleeve 46 retains and supports a packing member 47 which may for example be a neoprene washer. The packing member 47 faces the valve seat 49 comprising the lower end of the valve sleeve 34, and is adapted for movement against said valve seat 49. Also secured to the valve stem 38 is a tapered guide member 48, which insures a positive and accurate seating between the packing member 47 and the valve seat 49. The guide member 48 is preferably secured to the valve stem 38 in such fashion as to press downwardly upon the packing member 47, to insure a hermetical seal between said member 47 and the valve stem 38.

As is shown in Figures 1 and 2, a cap 50 having a washer 51 therein, may be screwed down upon the upper end of the casing 28, for a purpose described more fully below.

To use my air relief device, it is first connected to the liquid containing system, which for example may be a hot water radiator, expansion tank, gasoline storage tank, or the like, and the cap 50 screwed down tightly upon the casing 28. Thus the device is substantially hermetically sealed even though the valve unit 19 is held in the open position by the weight of the float 18. The system is then filled, and the cap 50 backed off sufficiently to permit air and gas to vent from the system at a slow rate. Otherwise liquid rushes into the casing 10, and may clog the valve seat 49 and sleeve 34 with dirt and scale. As the rising liquid causes the float 18 to rise within the casing 10 to the position shown in Figure 1, the spring 39 closes the packing member 47 against the valve seat 49, thereby closing the valve unit 19. As the device continues in operation, air and/or gas accumulate within the casing 10, causing the level of the liquid therein to fall, whereupon the float 18 moves downwardly. As the float 18 displaces downwardly, the lever 15 pivots about the pin 14, and forces the valve stem 38 downwardly against the resistance of the spring 39 (Figure 2). This opens the valve unit 19 and vents the air or gas within the casing 10 to the atmosphere, thereby permitting the level of liquid to once again rise in the casing 10 to the position shown in Figure 1. This cycle of operation is repeated indefinitely, to maintain the system free from objectionable air and gas.

If desired, the point at which the valve unit 19 opens to vent the air may be selectively varied in accordance with the amount of air entrapped therein, by adjusting the position of the hollow nut 32 along the threaded portion 31 of the casing 28. Thus, when the valve sleeve 34 is moved downwardly, the packing member 47 unseats from the valve seat 49 at a lower level of liquid than before. When the valve sleeve 34 is adjusted upwardly relative to the casing 28, then the reverse is true.

Advantageously, the tongue-shaped member 21 provides for positive drainage of the casing 10 at all times, whereby the level of liquid in said casing follows accurately the level of liquid in the balance of the system. If the tongue-shaped member 21 were not used, there would be a tendency as air or gas accumulates in the casing 10,

for the falling level of liquid within said casing to lag somewhat the level of the liquid in the balance of the system. This is especially noticeable when the system is drained, since the flow of liquid through the opening 22 is sluggish and may cease entirely due to the reduced pressure of the air or gas in the upper portion of the casing 10. The member 21 eliminates this undesirable characteristic of the prior art devices, the legs 23 and 24 counteracting the effects of surface tension and providing drain surfaces down which substantially all the liquid flows, while the space between said legs 23 and 24 serves as a passageway up which air and gas can flow. The tab 27 acts to deflect the downward flow of liquid and to make said flow more turbulent. As the downward flowing liquid strikes the tab 27, the member 21 is thereby caused to swing and vibrate, thus making the action of the member 21 even more effective.

Another special operating feature of the device results from the provision of the concavity 52 in the lever 15. I have discovered that the concavity 52 provides a far greater bearing surface between the enlarged portion 42 of the valve stem 38, and the lever 15, than the straight surfaced levers of the prior art constructions. At the same time, the force transmitted by the lever 15 to the enlarged portion 42, as the float 18 moves downwardly, is more nearly axial to the bore 30 of the casing 28, so that the valve stem 38 is pulled straight downwardly, rather than to one side. This substantially eliminates binding of the valve stem 38 on the valve sleeve 34, and makes operation of the entire valve unit 19 smoother and more accurate. In addition, the tapered guide member 48, best shown in Figure 5, insures that the packing member 47 is concentrically seated against the valve seat 49 each time the valve unit 19 is actuated. A positive seal between the member 47 and the valve seat 49 is thus obtained whenever the valve unit 19 is in the closed position of Figure 1. And because the packing member 47 is hermetically sealed against the stem 38, leakage between the neck portion 53 and the stem 38 is not critical.

By permanently securing the bonnet 11 to the casing 10, in the manner shown, the manufacture of the device is greatly simplified and the cost thereof reduced appreciably. While the float 18 and the supporting mechanism therefore are sealed within the casing 10, the operating parts of the valve unit 19 may still be serviced or replaced, notwithstanding the positive connection between the valve stem 38 and the lever 15. This feature results from the configuration of the aperture 44, wherein the enlarged portion 43 is placed on that end of the slot 45 distant from the pin 14. Thus, to remove the valve sleeve 34, the device is first uncoupled from the system, and turned upside down. The weight of the float 18 causes the lever 15 to swing toward the bonnet 11, and as the lever 15 moves past its normal operating limits, the enlarged portion 43 of the aperture 44 becomes aligned with the shoulder portion 42 of the valve stem 38. The valve sleeve 34 may then be readily removed by unscrewing the hollow nut 32. Advantageously, the configuration of the lower end of the member 21 prevents said member from falling into the casing 10 upon turning the device upside down.

It will thus be apparent that I have perfected an air relief device of improved construction, which is simple in design, relatively cheap to manufacture and in which the working parts of

the valve mechanism are readily removed for replacement or repair, and which in addition are adjustable to vary the point at which the valve is open to vent the air and gas in accordance with the amount of air and gas entrapped within the device. While I have shown and described a preferred embodiment of my invention, it is to be understood that said embodiment has been given by way of example only and that various changes and rearrangements of the details shown and described herein may be made without departing from the spirit of the invention, the scope of which is defined in the appended claims.

I claim:

1. An automatic air relief device, comprising a substantially cylindrical casing, a bonnet permanently fastened to one end of said casing, means at the other end of said casing for connecting said casing to a liquid containing system, a float disposed interiorly of said casing, a bracket secured to the interior surface of said bonnet, a link and a pin pivotally securing one end of said link to said bracket, the other end of said link pivotally secured to said float, said link having an aperture positioned along the length thereof and consisting of a narrow slot portion proximate said pivot pin and an enlarged portion at that end of said slot portion spaced from said pin, substantially all of said slot of said aperture disposed in an upwardly concave surface of said link, an adjustable, vertically disposed valve sleeve mounted in and extending through said bonnet adjacent to said bracket, a valve stem in said valve sleeve having an enlarged shoulder portion in said casing, said valve stem normally being in alignment with the slot portion of said aperture in said link, said shoulder portion of said valve stem insertable through said enlarged portion of said aperture, whereby said valve stem may be connected to said link by positioning said link outside of its normal operating displacement and adjacent to said bonnet and inserting said head portion of said valve stem through said enlarged portion of said aperture, said head portion engaging said narrow slot portion of said aperture upon returning said link to its normal operating position.

2. In an automatic air relief device including a casing, means for connecting said casing to a liquid containing system, a float disposed interiorly of said casing, and a vertically disposed, removable valve unit having an adjustable valve member mounted in and extending through the top wall of said casing, said valve member including a valve stem having a shoulder portion in the interior of said casing, means removably connecting said float to said valve stem, said

means comprising: a link, means connecting one end of said link to said float, pivot means connecting the other end of said link to said casing so that said link is beneath said valve member, said link having an aperture therein consisting of a narrow slot portion disposed substantially perpendicular to the axis of rotation of said pivot means and an enlarged portion at that end of said slot portion furthest removed from said pivot means, said aperture positioned so that said shoulder portion of said valve stem may be inserted through said enlarged portion when said link is displaced outside of its normal operating range and adjacent to said top wall, said narrow slot portion engaging said shoulder portion during normal operation of said device, during which normal operation downward movement of said float opens said valve unit to vent the interior of said casing to the atmosphere.

3. In an automatic air relief device including a casing, means for connecting said casing to a liquid containing system, a float disposed interiorly of said casing, and a removable valve unit extending through said casing, said valve unit including a valve stem having a shoulder portion in the interior of said casing, means removably connecting said float to said valve stem, said connecting means comprising: a link, means connecting one end of said link to said float, pivot means connecting the other end of said link to said casing so that a portion of said link is in alignment with said valve stem, said portion of said link having a slot therein the width of which is narrower than the width of said shoulder portion, said portion of said link also having an enlarged opening at that end of said slot furthest removed from said pivot means, said enlarged portion positioned so that said shoulder portion of said valve stem may be inserted therethrough when said link is displaced outside of its normal operating range toward said valve unit, said slot engaging said shoulder portion during normal operation of said device, during which normal operation downward movement of said float opens said valve unit to vent the interior of said casing to the atmosphere.
